W. E. ALLEN.

SYRINGE.

APPLICATION FILED JULY 6, 1912.

1,123,159.

Patented Dec. 29, 1914

UNITED STATES PATENT OFFICE.

WILLIS EDW. ALLEN, OF SAN DIEGO, CALIFORNIA.

SYRINGE.

1,123,159.

Specification of Letters Patent. Patented Dec. 29, 1914.

Application filed July 6, 1912. Serial No. 707,994.

To all whom it may concern:

Be it known that I, WILLIS E. ALLEN, a citizen of the United States, residing at San Diego, in the county of San Diego and State of California, have invented certain new and useful Improvements in Syringes, of which the following is a specification.

This invention comprehends certain new and useful improvements in surgical instruments and appliances, and relates particularly to syringes of the expanding type.

The invention has for its primary object a simple, durable, and efficient construction of syringe of this character designed for vaginal use the parts of which are so constructed and arranged that they may be easily and cheaply constructed and readily assembled and not liable to get out of order.

A further object of the invention is an improved vaginal syringe which will not be liable to injure the walls of the vagina, which in operation will thoroughly flush the parts without danger of overflowing or leaking, and which will be easily adjustable to different sizes as required.

Still another object of the invention is a syringe of this character in which the shield, through which the return flow passes, will effectually close the mouth of the vagina and prevent leaking, while at the same time will be comfortable when in position and not cause any inconvenience. And the invention also aims to generally improve devices of this class and to render them more useful and commercially desirable.

With these and other objects in view as will more fully appear as the description proceeds, the invention consists in the constructions, arrangements, and combinations of the parts that I shall hereinafter more fully describe and claim.

For a full understanding of the invention and the merits thereof, reference is to be had to the following description and accompanying drawing, in which:

Figure 1 is a sectional view of my improved expanding vaginal syringe, parts being shown in elevation and other parts broken away. Fig. 2 is a detail plan view of one of the parts of the shield, for holding the dilator fingers at one end in an adjustable manner; Fig. 3 is a fragmentary view illustrating one end of the device; Fig. 4

is a cross-sectional view through the expanding element of the syringe; Fig. 5 is a detail sectional view of a modified form of the shield, hereinafter specifically described; Figs. 6, 7 and 8 are detail views.

Corresponding and like parts are referred to in the following description and designated in the accompanying drawing by like reference characters.

Referring to the drawing, the numeral 1 designates the spray tube of my improved syringe, on one end of which is detachably mounted the expander head 2, secured on the tube in any desired way so that one head may be removed and replaced by another of larger or smaller size, as required. The head 2 is formed with any desired number of jet orifices 3 which are preferably obliquely disposed, as best seen in Fig. 4, whereby the healing and cleansing fluid, as it passes out through said orifices, will be in the form of a whirling spray. Preferably the body of the tube itself is also formed with jet orifices, designated 4, designed to enlarge the flushing area of the device.

The spray tube 1 is provided near one end with laterally projecting handle arms 5 by which it may be manipulated, and at such end with a nipple 6 designed for the attachment thereto of a supply tube 7 leading from a compression bulb 8.

Mounted upon the spray tube 1 is a cap-plate 9, the same being formed with a nipple 10 to which is attached a suction tube 11 leading to a suction bulb 12. The cap-plate 9 is formed with a marginal flange 13 by which it is designed for detachable connection to the grooved rim 14 of the body portion 15 of the shield. This body portion, in the present embodiment of the invention, may be formed of either solid or hollow (pneumatic) or soft or hard rubber, and it is to be particularly noted that the rim 14 of the body portion is formed with an open groove 16, whereby when the rim is pressed against the mouth of the vagina, a suction effect will be produced and all leakage prevented. The inner end of the body portion of the shield is formed, preferably, with an outwardly projecting flange 17, designed under ordinary conditions to engage, yieldingly, the walls of the vagina without uncomfortable pressure, and yet with suffi-

cient pressure to assist in preventing the medicament from passing, in its outward flow, around the outside of the shield.

The dilating fingers are designated 18. 5 These are preferably of spring metal or other substance or material and are square at their inner ends as clearly indicated at 19, so that they will not catch in the folds of the vagina and injure the same. The 10 said ends are adapted to ride upon the head 2 when the spray tube 1 is moved longitudinally so as to expand the device after it has been inserted in place, being finally lodged in the annular groove 20 with which 15 the head is formed (see Fig. 1).

The outer ends of the dilating fingers 18 are turned somewhat outward and then inward as indicated at 21, the inwardly turned extremities fitting within radial grooves 22 20 that are formed in a retaining disk 23 apertured to fit upon the spray tube 1, said extremities being clamped between said disk and the cap-plate 9 by means of screws 24, whereby the outer end of the dilator may be 25 laterally enlarged or contracted, as required.

From the foregoing description, together 30 with the accompanying drawing, the operation of my improved expanding vaginal syringe will be apparent. In the practical use of the device, a head of suitable size is slipped upon the end of the spray tube 1 and the outer ends of the dilating fingers 18 are adjusted as required, and the device inserted, in contracted condition, into the vagina.

35 The spray tube 1 is then pushed relatively inward, whereupon the inner ends of the fingers 18 will ride upon the head 2 and be expanded so as to hold the walls of the vagina suitably pressed apart. One of the 40 bulbs is then compressed and the other permitted to expand, whereby the healing and cleansing fluid will be forced into the organ and thoroughly flush the same, returning through the shield and out through the 45 suction tube 11. The shield will effectually prevent any leakage, and consequently the device can be used without fear of soiling bed or garments.

50 While the accompanying drawing illustrates the preferred embodiment of my invention, it is to be understood that the invention is not limited thereto, but that various changes may be made in the construction, arrangements, and proportions of the 55 parts without departing from the scope of the invention as defined in the appended claims. For example, reference is to be had to Fig. 5, wherein is illustrated another form of shield body portion. In that view the 60 said body portion, designated 15^a, is formed at its inner end with an outstanding flange 17^a like the flange 17 hereinbefore described, but at its outer end, instead of the grooved rim 14, a flanged rim 14^a is formed.

65 It will be seen that I have provided an im-

proved vaginal syringe possessing, among other advantages, the following: The inner ends of the dilator fingers are so formed that they will not be liable to catch in the folds of the vagina when withdrawing the device, the flushing device is so formed and arranged that its area and whirling spray will force everything out of the vagina instead of in it, the shield is so formed that it will effectually seal the mouth of the vagina, when the device is properly applied, and thus prevent any leakage, and the dilating fingers and the interchangeable head will enable the device to be easily adjusted to different sizes as required.

70 The dilator fingers may be made either, as illustrated in Figs. 1, 3 and 7, or, as illustrated in Fig. 8. It is to be understood that the fingers in Figs. 1, 3 and 8 are the same, the scale being so small, however, that it is 75 impossible to show the double lines in Figs. 1 and 3. It will, therefore, be understood that in each form or embodiment of the dilator fingers, they are formed of wire which is doubled upon itself at a middle point and which is squared at one extremity, as indicated at 19, or is round, as indicated at 19^a and filled in square, as indicated at 19^b in Fig. 8. In each embodiment of the dilating fingers, they are equally spaced apart 80 throughout their length and where they are connected together at the relatively free extremities, they are square and do not approach each other, the inner edges of the two lengths of the doubled wire being equally spaced apart throughout the length of the fingers, whereby no wedge-shaped space will be provided, which would be liable to catch the tissue and tear or otherwise injure it when the device is withdrawn. If desired, 85 the shield may have its outer flange provided with a bead, as indicated at 14^b, as clearly illustrated in Fig. 6.

90 What I claim is:—

1. A device of the character described, embodying a spray tube having a discharging head, dilating fingers and supports therefor at one end of the fingers, each of said fingers being formed of round wire doubled upon itself at a middle point to form spaced portions connected together at their free inner extremities, said members being straight and parallel for the major portion of their length and thence curved inwardly toward the head, the transverse portions of the wire which connect said members together at their free inner extremities presenting on their inner edges right angles with the adjoining edges of the said spaced members, whereby all tapering or wedge-shaped spaces at the free inner extremities of the fingers will be avoided and all liability of injuring the tissue upon the withdrawal of the device precluded.

110 2. A device of the character described, in-

cluding a spray tube and a shield, the shield tapering from its outer toward its inner end and being formed at both outer and inner ends with outstanding annular flanges, the flange at the outer end of the shield being provided with an open groove, as set forth.

3. A device of the character described, including a spray tube and a shield, the shield tapering from its outer toward its inner end

and provided at both outer and inner ends with outstanding flanges, for the purpose specified.

In testimony whereof I affix my signature in presence of two witnesses.

WILLIS EDW. ALLEN.
